DESIGN FOR AN EMBROIDERED TRIMMING OR SIMILAR ARTICLE

David Kugelman, Brooklyn, N. Y.

Application May 29, 1942, Serial No. 107,054

Term of patent 3½ years

To all whom it may concern:

Be it known that David Kugelman, a citizen of the United States and resident of Brooklyn, in the county of Kings and State of New York, has invented a new, original, and ornamental Design for an Embroidered Trimming or Similar Article, of which the following is a specification, reference being had to the accompanying drawing, forming part thereof, in which the figure is a plan view of an embroidered trimming or similar article in accordance with my new design.

The dotted lines on the drawing outline substantially a design unit, which unit is repeated in regular succession as indicated by the extensions beyond the unit boundaries.

I claim:

The ornamental design for an embroidered trimming or similar article, substantially as shown.

DAVID KUGELMAN.
